PORTABLE BOTTLE VENDOR

Joseph E. Hagstrom and Olaf C. Olsen, Kansas City, Mo., assignors to C. Earl Hovey, trustee, Kansas City, Mo.

Application October 25, 1940, Serial No. 362,734

13 Claims. (Cl. 312—36)

This invention relates to vending machines of the portable type wherein a relatively few packages may be kept for cooling and from which said packages may be removed, one at a time, and one of the salient objects is the provision of a comparatively small bottle vendor having therein unique means for maintaining the temperature within the case thereof, at a predetermined point.

Another object of this invention is to provide a portable bottle vendor having unique means for imparting step-by-step movement to a dispensing plate, which movement is preferably controlled through coin actuated means associated with a novel locking element, the nature of which serves to releasably hold the aforesaid dispensing plate in one of a number of positions where the opening thereof is in alignment with one of the underlying packages or bottles, as the case may be.

This invention has for a yet further aim, the provision of simple, unique, durable and novel coin controlled means mounted directly upon the revolvable dispensing plate of the portable vendor and directly associated with a manually movable slide, the path of travel of which is determined by the presence of a coin in the said means, and by inclined faces on a part of the case of the vendor, the position of which is such as to cause movement of the slide as the aforesaid revolvable plate is rotated on its axis.

A still further object of this invention is the provision of a portable bottle vendor, the nature of which permits producing a large number thereof, each capable of cooling and holding for delivery a relatively small number of bottles, whereby small offices or the like may be serviced without an investment such as required by conventional vending machines now in general use.

Other objects of the invention including important specific details of construction, manner of making a portable cooler in accordance with the instant invention, and mode of operating the same, will appear during the course of the following specification, referring to the accompanying drawing wherein:

Figure 1 is a fragmentary top plan view of a portable bottle vendor made to embody the present invention.

Fig. 2 is a vertical central sectional view through the same, taken on line II—II of Fig. 1.

Fig. 3 is an inverted plan view of the hinged cover forming a part of the vendor.

Fig. 4 is an enlarged fragmentary detailed

sectional view through a portion of the cover taken on line IV—IV of Fig. 3.

Fig. 5 is a fragmentary vertical sectional view taken on line V—V of Fig. 4.

Fig. 6 is a similar view taken on line VI—VI of Fig. 4.

Fig. 7 is a sectional view taken on line VII—VII of Fig. 4.

Fig. 8 is a detailed fragmentary sectional view taken on line VIII—VIII of Fig. 3.

Fig. 9 is a fragmentary perspective view illustrating a cooling medium container.

Fig. 10 is a similar view illustrating a container made to embody a modified form of the invention; and

Fig. 11 is a fragmentary sectional perspective view of a cooling medium container usable in the vendor and embodying a still further modification of the invention.

20 Case 12 of the portable vendor should be made relatively small to contain bottles or other packages 14 arranged in a circumscribing path below a delivery opening to be hereinafter described.

Bottles 14 are positioned in stalls 16 of bottle 25 rack 18 and this rack may be bodily lifted from within case 12 by grasping one or more handles 20. Floor 22 of bottle rack 18 has a well 24 at the center thereof for the reception of cooling medium container, such as illustrated in Figs. 9, 10 and 11.

The size of the vendor necessitates using an effective cooling medium and it has been found that dry ice 26, a quantity of which is shown in container 28 in Fig. 2, is satisfactory where the 35 said container is built to allow dry ice 26 to slowly sublimate and maintain an even temperature not lower than that which will maintain the bottles and their contents at from 36° to 44° F.

Container 28 is removable and the base 30 40 thereof is formed of non-conducting material such as wood that fits into well 24 and supports sheet metal double annular walls 32 between which is packed insulating substance 34.

Container 28 has an open upper end and the 45 cool air spills over the edge of the container 28 at the top thereof. An even and desirable transfer of heat is established throughout the entire length of container 28 however, because sheet metal walls 32 are brought together along four 50 vertical lines to present a metal-to-metal relation capable of heat transfer laterally toward bottles 14 arranged in the circumscribing path which skirts container 28.

The number of bottles to be stored in case 12, 55 the temperature desired, the length of time that

bottles 14 are normally in the case before being withdrawn, and the amount of dry ice 26, will have a direct bearing upon the type of metal employed to produce walls 32, but copper has been found preferable where 12 bottles are to be vended from a case 12 having the proportions illustrated in the drawings.

Another form of container (Fig. 10) is generally designated by the numeral 36 and comprises a base 38 of wood or other insulating material, from one side of which extends inner and outer walls 40 and 42 between which insulating material 44 is packed. Inner wall 40 projects upwardly, outwardly and thence downwardly along the outer surface of outer wall 42 to present an uninterrupted sheet metal member that is highly conductive and which insures heat exchange between the air surrounding bottles 14 and dry ice 26 within container 36. The length of the downwardly projecting portion of wall 40 designated by the numeral 46, may be varied to suit conditions, for the longer this portion 46 is made the greater the heat exchange will be.

Fig. 11 illustrates the manner of constructing another type of container usable in well 24 and is broadly designated by the numeral 48. This container 48 has a base 50 formed of wood or insulating material, and supporting spaced apart sheet metal walls 52 and 54, between which insulating material 56 is packed. In this instance, inner wall 52 extends across the bottom of the container to form a floor 58 immediately above base 50.

A top 60 is removably secured to this container 48 through the medium of bayonet slot structure 62 and gasket 64 positively seals the container.

Ducts 66 extending upwardly and outwardly through walls 52 and 54 permit the escape of gas from within container 48 as the dry ice therein sublimates. These ducts 66 are relatively small in cross sectional area, and therefore, create a pressure that forces gas outwardly and into the chamber formed within case 12, which holds bottles 14. Such arrangement of parts will insure against stratification and air currents are set up to preclude the formation of voids or static air pockets.

Either of the three forms of container shown in Figs. 9, 10 and 11, is usable in case 12 and will adequately cool all bottles 14 therein. Case 12 is formed of thick walls of insulating material and the cover 68 thereof has an opening of appreciable size therein that is closed by rotatable plate 70. Cover 68 is hingedly mounted on case 12 as at 72 and a lock 74 is used to hold cover 68 in place against movement by unauthorized persons.

Rotatable plate 70 is disc-shaped and the annular edge thereof is formed with radially extending sectional flanges 76 and 78, one of which precludes upward or outward movement of plate 70, while the other rests upon annular notched rack 80 to prevent inward or downward movement thereof. This rack 80 is carried by hinged cover 68 and has a number of spaced apart notches 82 to receive dog 84 mounted on housing 86 secured directly to plate 70.

Plate 70 has a delivery opening 88 closed by door 90 that is yieldably held in the closed position by spring 92 wound about hinge pin 94 journaled in ears 96 integral with plate 70. A knob 98 on door 90 affords convenient grip for the operator.

Cover 68 has a track 100 mounted thereon immediately below rack 80. This track has a series

of notches 102 formed therein adjacent to each of which is an inturned radially projecting ear 104 having an inclined face 106 and an arcuate face 108. It is notable that both rack 80 and track 100 are stationary with respect to plate 70 and that as said plate is rotated about its axis dog 84 will drop into notches 82 to allow movement in but one direction.

The numeral 110 designates a slide of special form having a tongue 112 extending radially from one end thereof. A roller 114 on tongue 112 engages track 100 and rides along inclined surface 106 and edge 103 as will be more fully hereinafter described.

15 Slide 110 is movably mounted in housing 86 and the inner end is rebent upon itself to present a wall 116 having an opening 118 therethrough, and a flange 120 in spaced relation to the major part of the slide.

20 A notched wall 122 secured to end wall 116 of slide 110 cooperates with said wall 116 in presenting a coin receiving pocket 124. A pin 126 on plate 70 is engaged by one end of spring 128, the other end of which is fastened to slide 110 25 to yieldably maintain the same at one end of its path of travel where tongue 112 is in one of notches 102, when delivery opening 88 is above one of stalls 16. A shelf 130 on housing 86 supports the weight of a coin 132 when one is in 30 pocket 124. A coin box 134 removably held in place by a latch 136 receives coins 132 when the same are forced from position on shelf 130.

An operating handle of lever type 138 is carried by plate 70. A vertical shaft 140 extends 35 through plate 70 and is journaled in the boss 142 thereon. This shaft 140 is shouldered and a nut 144 maintains one end of a link 146 in place thereon to be moved therewith. This link may be keyed to shaft 140 as shown in Fig. 7.

40 While one end of link 146 is keyed to shaft 140 the other end thereof is pivotally joined as at 148 to one end of link 150 yieldably held at one end of its path of travel by a spring 152. Slot 154 of link 150 receives screw 156 mounted to 45 project downwardly from flange 120.

Link 150 is in alignment with opening 118 and notch 158 of wall 122 so as to strike coin 132 during the normal movement of handle 138. Nut 144 is in the path of travel of link 150 as it moves laterally due to the swinging of link 146 and limits such movement, as will be hereinafter described.

Coin 132 is introduced through coin slots 160 in plate 70 and when the coin is so inserted, to be in the position shown in Fig. 4, the operation of the apparatus is as follows:

Assuming that the parts of the vendor are in the position in the drawings, a coin 132 is dropped through slot 160 into compartment 124 where it rests upon shelf 130. Upon rotating lever 138 about its own axis, links 146 and 150 will be moved to bring the free end of the latter against coin 132, whereupon force will be imparted to slide 110 to move the same to the intermediate position shown in dotted lines of Fig. 4.

Obviously, if no coin is present, such movement cannot occur and the end of link 150 will freely enter notch 158 of wall 122.

The movement of slide 110 to the said dotted position withdraws tongue 112 from one of notches 102 in track 100. Immediately upon clearing the notch further movement of lever 138 is precluded because the right hand end of slot 154 (Fig. 7), strikes screw 156 to arrest the said movement. The operator however, will con-

tinue applying force to lever 138 to bodily move plate 70 in the direction of the arrows shown in Fig. 1.

Roller 114 on slide 110 will thereupon engage part of the cam face of track 100, which has previously been defined as the inclined face 106. As the roller so moves over this face 106, slide 110 will be forced to the left (Fig. 4), to the position shown in the second dotted line position. Pin 156 being in slot 154 will not restrict the movement of slide 110 and such travel on the part of the slide will carry coin 132 off of shelf 130 and allow it to drop into coin box 134.

Roller 114 will move along the innermost arcuate face 108 until it reaches shoulder 162, whereupon it will be drawn back against track 100 by spring 128. The roller will ride along the track until the next notch 102 is encountered, whereupon both tongue and roller 112 and 114 respectively, will enter and arrest further movement of plate 70. When the operator releases lever 138, spring 152 will move both links 146 and 150 back to the point of beginning.

To prevent reversal of movement on the part of plate 70, dog 84 when in any position around annular track 80, other than that shown in Fig. 3, will drop into one of notches 82 immediately after tongue 112 has been drawn from a notch 102 and therefore, if the operator attempts to reverse the movement of plate 70 from normal while roller 114 is riding over surface 106 and 108 of the cam face of track 100, dog 84 will prevent such undesirable action. When roller 114 jumps behind shoulder 162, plate 70 is further secured against movement in a direction opposite to that intended. Notches 102 are spaced apart a distance where opening 88 will be in alignment with a stall 16 in rack 18 whenever tongue 112 and roller 114 are in a notch 102.

After a complete movement around the circumscribing path of stalls 16, tongue 112 will strike stop 164. This stop extends inwardly so far that even with a coin dropped into place, as shown in Fig. 4, operation of the plate 70 cannot occur. The owner of the equipment may then unfasten lock 74, move cover 68 to the open position and then reset the parts to be as shown in Fig. 3. When the parts are in this set position, dog 84 is in one of notches 82 in track 80 so that when a coin is inserted, plate 70 cannot be accidentally rotated to a point where the tongue 112 is again behind stop 164.

Notch 158 in wall 122 is formed as shown in Fig. 5 and has wings 166 to engage the upper marginal edge of coin 132 if it is of the proper denomination and size. If a coin or slug of smaller size is inserted, it will fall from shelf 130 into the coin box without allowing slide 110 to be withdrawn from its locked position.

The simple mechanism is located on the underside plate 70 near the periphery thereof and bottles 14 are arranged in a path which is square to allow a relatively large number to be stored in a small case.

The temperature of these bottles may be controlled by the use of containers such as shown in Figs. 9 to 11 inclusive, and as has been hereinabove set down, these containers are unique in that the heat exchange produced may be determined and altered, and further, circulation of air within case 12 may be set up.

Portable, inexpensive vendors of the type described and illustrated are now desirable for small organizations may be serviced economically by providing a container for each depart-

ment or group of employees. The container serves as a case for a few bottles and because of its inexpensive nature, there may be a large number of cases within which to distribute 5 bottled goods without a prohibitive investment.

There is no need for coin detecting mechanism of complicated character in equipment of the type contemplated by this invention, for the portable vendor is not usually placed in public 10 locations.

Certain advantages arising from the invention have been made clear but it will become obvious to one skilled in the art that a vast number of valuable benefits not discussed herein, are available to one enjoying the concepts hereby disclosed.

Having thus described the invention, what is claimed as new and desired to be secured by Letters Patent is:

20 1. In a vending machine of the character described a closed case having an opening in the top thereof; a rotatable plate closing said opening and provided with a delivery opening; an operating lever on the plate; a rack for packages 25 being vended comprising a plurality of stalls arranged in a circumscribing path below the delivery opening; a notched track on the case around the rotatable plate; a slide mounted on the plate having a portion movable to and from a position projecting into the respective notches to prevent rotation of the plate; and coin controlled means for withdrawing said portion of the slide from within the notches.

2. In a vending machine of the character described a closed case having an opening in the top thereof; a rotatable plate closing said opening and provided with a delivery opening; an operating lever on the plate; a rack for packages 35 being vended comprising a plurality of stalls arranged in a circumscribing path below the delivery opening; a notched track on the case around the rotatable plate; a slide mounted on the plate having a portion movable to and from a position projecting into the respective notches to prevent rotation of the plate; and coin controlled means for withdrawing said portion of the slide from within the notches, said track having inclined faces thereon adjacent to the notches for engaging said slide to further move the same 40 as the plate is manually rotated after its said portion has been withdrawn from one of the notches.

3. In a vending machine of the character described a closed case having an opening in the top thereof; a rotatable plate closing said opening and provided with a delivery opening; a rack for packages being vended comprising a plurality of stalls arranged in a circumscribing path below the delivery opening; a notched track on the case around the rotatable plate; a slide mounted on the plate having a portion movable to and from a position projecting into the respective notches to prevent rotation of the plate; a pivoted 50 operating lever on the rotatable plate to one side of the axis of rotation thereof; parts connecting the operating lever with the slide for withdrawing said portion of the slide from within the notches when the lever is moved about its pivotal connection from a normal position; and elements on the track for further moving the slide after the plate is released and caused to move about its axis by force exerted on the lever.

4. In a vending machine of the character described a closed case having an opening in the top thereof; a rotatable plate closing said opening 55

and provided with a delivery opening; a rack for packages being vended comprising a plurality of stalls arranged in a circumscribing path below the delivery opening; a notched track on the case around the rotatable plate; a slide mounted on the plate having a portion thereof movable to and from a position projecting into the respective notches to prevent rotation of the plate; a pivoted operating lever on the rotatable plate to one side of the axis of rotation thereof; parts connecting the operating lever with the slide for withdrawing said portion of the slide from within the notches when the lever is moved about its pivotal connection from a normal position; and elements on the track for further moving the slide after the plate is released and caused to move about its axis by force exerted on the lever, said lever having a stop for limiting its movement about its pivotal connection in one direction when the slide has reached a position where the said portion is free from the notches of the track.

5. In a vending machine of the character described a closed case having an opening in the top thereof; a rotatable plate closing said opening and provided with a delivery opening; a rack for packages being vended comprising a plurality of stalls arranged in a circumscribing path below the delivery opening; a notched track on the case around the rotatable plate; a slide mounted on the plate having a portion thereof movable to and from a position projecting into the respective notches to prevent rotation of the plate; a pivoted operating lever on the rotatable plate to one side of the axis of rotation thereof; parts connecting the operating lever with the slide for withdrawing said portion of the slide from within the notches when the lever is moved about its pivotal connection from a normal position; elements on the track for further moving the slide after the plate is released and caused to move about its axis by force exerted on the lever, said lever having a stop for limiting its movement about its pivotal connection in one direction when the slide has reached a position where the said portion is free from the notches of the track; and a spring for returning the lever to its normal position.

6. In a vending machine of the character described a closed case having an opening in the top thereof; a rotatable plate closing said opening and provided with a delivery opening; a rack for packages being vended comprising a plurality of stalls arranged in a circumscribing path below the delivery opening; a notched track on the case around the rotatable plate; a slide mounted on the plate having a portion thereof movable to and from a position projecting into the respective notches to prevent rotation of the plate; a pivoted operating lever on the rotatable plate to one side of the axis of rotation thereof; parts connecting the operating lever with the slide for withdrawing said portion of the slide from within the notches when the lever is moved about its pivotal connection from a normal position; elements on the track for further moving the slide after the plate is released and caused to move about its axis by force exerted on the lever, said lever having a stop for limiting its movement about its pivotal connection in one direction when the slide has reached a position where the said portion is free from the notches of the track; and yieldable means for urging the slide toward the notches and into operative relation with the said elements on the track.

7. In a vending machine of the character de-

scribed a closed case having an opening in the top thereof; a rotatable plate closing said opening and provided with a delivery opening; a rack for packages being vended comprising a plurality of stalls arranged in a circumscribing path below the delivery opening; a notched track on the case around the rotatable plate; a slide mounted on the plate having a portion thereof movable to and from a position projecting into the respective notches to prevent rotation of the plate; a roller on the slide; inclined faces on the track in the path of travel of the roller on the slide to further move the same as the plate is moved about its axis after the said portion of the slide has been withdrawn from one of the notches; and means for returning the slide to its normal position.

8. In a vending machine of the character described a closed case having an opening in the top thereof; a rotatable plate closing said opening and provided with a delivery opening; a rack for packages being vended comprising a plurality of stalls arranged in spaced relation in a circumscribing path below the delivery opening; a pair of notched tracks rigid with the case extending around the rotatable plate; a dog mounted for rotation with the rotatable plate for engagement with the notches of one of the tracks, said notches in one plate being formed to allow rotation of the plate in one direction and to preclude rotation in the opposite direction; a slide mounted on the plate near the periphery thereof for movement to and from a position into the notches of the other track; a shoulder and a cam face on the last mentioned track adjacent to each notch thereof respectively; and coin controlled means for withdrawing said slide from within the notches and drawing the same across the adjacent cam after such withdrawal and while the plate is being rotated, said notches of the tracks being closer together than the distance between the notch engaging portion of the slide and said dog, whereby to cause the slide to lock the plate against movement in either direction with the delivery opening thereof over a stall in the rack, when the dog is in a position other than within the notch.

9. In a vending machine of the character described a closed case having an opening in the top thereof; a rotatable plate closing said opening and provided with a delivery opening; a rack for packages being vended comprising a plurality of stalls arranged in spaced relation in a circumscribing path below the delivery opening; a pair of notched tracks rigid with the case extending around the rotatable plate; a dog mounted for rotation with the rotatable plate for engagement with the notches of one of the tracks, said notches in the one plate being formed to allow rotation of the plate in one direction and to preclude rotation in the opposite direction; a slide mounted on the plate near the periphery thereof for movement to and from a position into the notches of the other track; a shoulder and a cam face on the last mentioned track adjacent to each notch thereof respectively; and coin controlled means for withdrawing said slide from within the notches and drawing the same across the adjacent cam after being withdrawn and while the plate is being rotated, said notches of the tracks being closer together than the distance between the notch engaging portion of the slide and said dog, whereby to cause the slide to lock the plate against movement in either direction with the delivery opening thereof over a stall in the rack when the dog is in a posi-

tion other than within the notch, said dog being movable into the notches of the said one track to preclude movement of the plate in one direction as the slide is moving across the cam face during movement of the plate in the other direction.

10. In a vending machine of the character described a closed case having an opening in the top thereof; a rotatable plate closing said opening and provided with a delivery opening; a rack for packages being vended comprising a plurality of stalls arranged in spaced relation in a circum-scribing path below the delivery opening; a pair of notched tracks rigid with the case extending around the rotatable plate; a dog mounted for rotation with the rotatable plate for engagement with the notches of one of the tracks, said notches in the one plate being formed to allow rotation of the plate in one direction and to preclude rotation in the opposite direction; a slide mounted on the plate near the periphery thereof for movement to and from a position into the notches of the other track; a shoulder and a cam face on the last mentioned track adjacent to each notch thereof respectively; and coin controlled means for withdrawing said slide from within the notches and drawing the same across the adjacent cam after being withdrawn and while the plate is being rotated, said notches of the tracks being closer together than the distance between the notch engaging portion of the slide and said dog, whereby to cause the slide to lock the plate against movement in either direction with the delivery opening thereof over a stall in the rack when the dog is in a position other than within the notch, said dog being movable into the notches of the said one track to preclude movement of the plate in one direction as the slide is moving across the cam face during movement of the plate in the other direction, said cam face having a radial shoulder engagable behind the slide to prevent movement of the plate in said last mentioned one direction after the dog has travelled past a notch of the said one track.

11. In a vending machine of the character described a case having an opening in the top thereof; a rotatable plate closing said opening and provided with a delivery opening; a track

on the case around the plate and having a series of notches, cam faces and shoulders on the track; a slide on the plate engaging one of the notches when in a normal position; and coin controlled means for withdrawing the slide from the notches, said slide being shiftable by engagement with one of the cam faces as the plate is rotated in one direction to render the coin controlled means inoperative before reaching the next notch.

12. In a vending machine of the character described a case having an opening in the top thereof; a rotatable plate closing said opening and provided with a delivery opening; a track on the case around the plate and having a series of notches, cam faces and shoulders on the track; a slide on the plate engaging one of the notches when in a normal position; and coin controlled means for withdrawing the slide from the notches, said slide being shiftable by engagement with one of the cam faces as the plate is rotated in one direction to render the coin controlled means inoperative before reaching the next notch, said slide having a yieldable element for maintaining the same against the cam faces and within the notches.

13. In a vending machine of the character described a case having an opening in the top thereof; a rotatable plate closing said opening and provided with a delivery opening; a track on the case around the plate and having a series of notches, cam faces and shoulders thereon; a slide on the plate engaging one of the notches when in a normal position; and coin controlled means for withdrawing the slide from the notches, said slide being shiftable by engagement with one of the cam faces as the plate is rotated in one direction to render the coin controlled means inoperative before reaching the next notch, said slide having a spring to force the same behind said shoulder immediately after the coin controlled means has been rendered inoperative to prevent rotation of the plate in the opposite direction.

JOSEPH E. HAGSTROM.
OLAF C. OLSEN.
